HOOD FOR CAR DUMPERS

Arthur F. Case, Cleveland, and Joseph P. Doyle, Lakewood, Ohio, assignors to The Wellman Engineering Company, Cleveland, Ohio, a corporation of Ohio

Application July 13, 1933, Serial No. 680,276

32 Claims. (Cl. 214—123)

This invention relates to car dumpers of the type having a car receiving cradle which is turned to dump a car supported by the cradle and more particularly to hood means for a car dumper to retard and control the shifting of the material in the car and the discharge of the same therefrom when the cradle is turned.

As the tilting or dumping movement of the cradle of a car dumper commences the material in the car being dumped starts to shift toward the dumping side. This shifting movement of the material toward the dumping side of the car before the car reaches full dumping position is disadvantageous in any type of dumper and it is especially so in dumpers using car clamps of the type wherein the turning movement of the cradle moves the car into engagement with the clamps.

Furthermore, the tilting or dumping movement of the cradle of a car dumper, particularly when there has been a shifting of the material in the car being dumped during the early stages of the movement, acts to throw the material at the far side and bottom of the car outwardly into the discharge pan at a distance from the dumper tower or frame. This results in considerable breakage of the material being dumped unless the outflow of the material from the car is retarded. This breakage is serious irrespective of the particular material being dumped, but it is more serious when the material is coal.

Another cause of breakage of the material is the fact that the dumping movement of the cradle causes the contents of the car, especially if it has shifted previously, to be discharged suddenly therefrom in a large volume resulting in the material sliding down the discharge pan in a great mass and at a substantial speed.

The principal object of the present invention is to provide improved means in a car dumper for substantially reducing the amount of breakage in the material caused by the dumping movement of the cradle.

Another object of the invention is to provide means in a car dumper for substantially eliminating or reducing the shifting movement of the material in the car being dumped toward the dumping side of the car during the early stages of the turning movement of the cradle.

Since it is customary in positioning a car upon the cradle of a car dumper to have a man ride the car onto the cradle and to manually set the car brakes at the proper time, it is necessary that the means, specified above, be of such character as not to interfere with the car rider or to present

a dangerous hazard for the rider when the cradle is in car receiving position.

Another important object of the invention is to provide improved means in a car dumper for reducing the breakage of the material during the dumping operation, which means is of such character as not to be unsafe in that when the cradle of the dumper is in car receiving position said means will be automatically positioned so as not to interfere with or injure a man riding a car onto the cradle.

Another object is to provide means in a car dumper, such as specified above, whereby substantially all of the material being dumped must pass into the discharge pan of the dumper adjacent to the dumping point, that is, adjacent the dumping frame or tower and the pan girder.

Another object is to provide means in a car dumper, such as specified above, that is capable of functioning with cars of different height and length.

A further object is to provide means in a car dumper, as previously specified, which will adapt itself to the varying heights of the load of material in the car being dumped.

A further and more specific object is to provide means in a car dumper, such as previously specified, wherein said means will be positively held against movement during the dumping operation, thus assuring efficiency and safety thereof in use.

Another object is to provide in a car dumper means, such as previously specified, which will not interfere with the operation or effectiveness of the car clamps.

Additional and further objects and advantages will become apparent during the detailed description of an embodiment of the invention now about to be described and which, for purposes of illustration, is shown as applied to a car dumper of the lifting and tilting type, although, of course, it could be applied to a car dumper of the turn-over type in which the cradle of the car dumper revolves about a fixed pivot and has no vertical hoisting movement previous to its dumping rotation, or to a car dumper of the rolling type in which the car is clamped in a barrel-shaped cradle that is rolled up an inclined track to a point where the contents of the car are to be dumped, or to a car dumper of any other type.

Referring to the accompanying drawings illustrating such embodiment:

Fig. 1 is a side elevational view of a car dumper of the lifting and tilting type, the cradle being shown in car receiving position in full lines and

in its raised or fully tilted position in dash and dot lines, certain of the parts of the dumper being shown diagrammatically since they form per se no part of the present invention and are well understood in the art;

Fig. 2 is a fragmentary rear elevational view of the cradle of the car dumper shown in Fig. 1 with the hoods in the raised or inoperative position, such as they assume when the cradle is in car receiving position;

Fig. 3 is a fragmentary top plan view of the cradle of the dumper with the hoods shown in the operative or car covering position, the outline of the car, as well as one of the car clamps of the 15 cradle being shown in dash and dot lines;

Fig. 4 is an enlarged view partly in side elevation and partly in section of the cradle of the dumper with the embodiment of the invention illustrated thereon in full lines when the cradle 20 is in car receiving position and in dash and dot lines before the cradle reaches car receiving position and the car is empty;

Fig. 5 is a fragmentary view of the cradle shown in Fig. 4 and illustrates the position of the parts 25 when the cradle has been turned 90° during the dumping operation;

Fig. 6 is an enlarged fragmentary detailed view showing the position of the retaining pawl for the 30 sliding frame of the hood when the cradle is in car receiving position;

Fig. 7 is a view similar to Fig. 6, but illustrates the positions of the parts shown in Fig. 6 after the cradle has turned approximately 90° during the dumping operation;

Fig. 8 is a fragmentary elevational view taken 35 from the right-hand side of Fig. 6, and

Fig. 9 is an enlarged top plan view of the portion of the dumper enclosed in dotted circle A of Fig. 3, certain parts of the dumper being 40 broken away to more clearly show underlying parts thereof.

Referring to the accompanying drawings the car dumper is shown as comprising a tower 10 formed of suitable structural members and having 45 a vertically movable tiltable cradle 11 arranged therein and slidably along suitable vertical guides, the vertical movement of the cradle in the tower being effected by cables or ropes connected to the cradle and to suitable drums and passing around 50 sheaves located at the top of the cradle, as is well understood in the art. The cradle 11 is provided with a platen 12 having tracks thereon to receive a car 13, such platen preferably being shiftable laterally by suitable means to cause the car 55 to be moved over beneath the car clamps on the dumping side and to engage the bumper at such side as the cradle starts to turn and to restore the platen to center position at the end of the return movement of the cradle after the dumping operation.

The cradle 11 is arranged to be first hoisted vertically to the desired dumping point and then to be rotated about a horizontal axis extending longitudinally of the cradle so that the material in 65 the car on the cradle will be discharged from the car over the side or dumping edge thereof. The point where the vertical hoisting of the cradle terminates and its dumping rotation commences is ordinarily adjustable to suit different conditions, while the rotation of the cradle is accomplished by the engagement of pivot pins carried by the cradle with suitable hooks arranged on a vertically adjustable girder movably supported and guided by the framework of the tower. The 70 means for tilting the cradle and the adjustable 75

girder referred to have not been illustrated herein, since per se they form no part of the present invention and are well understood in the art, it being deemed sufficient to show the cradle and car in the tilted dumping position by means of 5 dot and dash lines (see Fig. 1).

A portion of a discharge pan or bin 14 is illustrated in Fig. 1 and it is into such pan or bin that the contents of the car are dumped by the dumping movement of the cradle. The inner end of 10 the pan is ordinarily hingedly connected to the adjustable girder referred to above and is of such width at its inner end as to be capable of receiving material from the longest car which can be handled by the dumper, while the outer end of 15 the pan is ordinarily supported by ropes connected to such end and passing over the top of the main framework of the tower.

Referring again to the cradle 11, it will be seen that certain of the vertically extending arms of 20 the cradle at the dumping side thereof have secured thereto bumper members 15 in which clamp hooks 16 are slidably mounted and which have downwardly extending portions 17 adapted to engage the base of the dumper when the cradle 25 is in its lowered position to cause the clamp hooks to move upwardly away from the top edge of the car after the latter has been dumped and the cradle is returned to car receiving position. Car clamp beams 18 are pivotally connected at 19 to 30 the clamp hooks 16 by means of connecting straps 20 secured to the webs of the beams and forming yokes straddling the hooks 16. The clamp beams 18 are of such length as to extend transversely 35 across the cradle and are held in elevated position when the cradle is lowered by means of cables or ropes 21 connected to the members 15 and passing through suitable sheaves or other means on the clamp beams and other sheaves located at the top of the tower to counterweights (not 40 shown) movable vertically of the tower in suitable guides. This arrangement of the car clamps is well understood in the art, as is also the manner in which the clamps function when the cradle is raised and tilted; that is, when the cradle moves 45 vertically upwardly the hooks 16 stand stationary until engaged by the top edge of the car at the dumping side thereof, after which the hooks travel with the car and the clamp beams swing downwardly across the top of the car until the 50 tilting or dumping movement of the cradle causes the counterweights connected to the cables 21 to bring the clamp beams firmly against the top of the car and hold the same in such position against the weight of the car and its contents during 55 the dumping operation to thereby maintain the car in position upon the tracks of the cradle. It will be understood that there may be any number of these car clamps as desired, although in the present embodiment four such clamps have 60 been illustrated. It will further be understood that the means for raising the hooks 16 out of engagement with the top of the car when the cradle is in its car receiving position may take various forms and that the specific construction 65 disclosed herein for that purpose is merely illustrative.

At the side of the cradle opposite to the dumping side thereof the cradle platform has secured thereto a longitudinally extending girder frame 70 22 formed of suitable structural members. Extending upwardly from the girder frame 22 are standards 23, there being four of these standards shown in the present embodiment (see Fig. 2) and each standard being formed of oppositely 75

facing channels 23a interconnected by a plate 23b (see Fig. 9) on the inward or cradle side of the standards. It will be understood that the standards 23 are suitably connected at their lower ends to the girder frame 22 by means of angles, gussets and like structural members commonly used for such purpose.

The hood for the car dumper comprises a hood frame which is vertically slidable on the standards 23 and is formed of vertically extending channels 24 to the bases of which are secured straps 25 extending to the rear side of the cradle and provided at their ends with laterally turned portions 25a lying adjacent to and back of the rear flange of the channels 23a. The channels 24 also have secured thereto plates 25b which extend along the front side of the plates 23b of the standards. The sliding frame of the hood is, in the present embodiment, formed in three separate sections with the two outer sections having channels 24 lying adjacent to the two end standards 23 and channels 24 lying adjacent to the two intermediate standards 23. The intermediate section of the sliding frame has its channels 24 lying adjacent to the two intermediate standards 23, it being noted that all of the channels 24 are held for vertical movement on the standards by means of the laterally turned portions 25a and the plates 25b.

The channels 24 of each frame section are connected at their lower ends by downwardly facing channels 26 extending longitudinally of the frame section and intermediate their ends by downwardly facing channels 27 also extending longitudinally of the section. The channels 26 and 27 of each section are connected intermediate their ends by vertically extending angle bars 28 secured thereto and projecting above the channels 27. The sliding frame sections are further braced and reenforced by brace rods, wires or other suitable means, indicated generally at 29, as is well understood in the art.

The sliding frame sections are counterbalanced in their movements on the standards 23 by means of counterweights 30 mounted in suitable guides on the rear of the tower or frame 10 of the dumper and connected to ropes 31 passing over suitable sheaves and connected at their opposite ends to means carried by the sliding frame sections and later to be referred to more in detail, it being noted that there are two counterweights connected to each section of the sliding frame.

The sliding frame carries the hoods proper which are pivotally supported upon the channels 27 of the frame sections. The channels 27 are provided on their upper side with brackets 32 between which brackets extend structural members 33 that are pivotally mounted upon pins 34 carried by the brackets 32 and extending through the members 33. The members 33 extend transversely of the cradle toward the dumping side and also rearwardly of the cradle beyond the channels 27. The two end sections of the sliding frame have four of the members 33 pivotally connected thereto, while the intermediate section of the frame has six of these members pivotally connected thereto for a reason later to become apparent.

The members 33 together with plates 35 secured thereto form the hood proper for the cradle, it being noted that every two adjacent members 33 carry a plate 35 and that the two end sections of the frame each have two swinging hoods thereon, while the middle section of the frame is provided with three swinging hoods making in all a

total of seven swinging hoods. The purpose of forming the frame in sections and mounting thereon separate swinging hoods is to enable the construction to adapt itself to cars of different lengths, as well as to adapt itself to the varying heights to which the car may be loaded with the material, since the hoods engage the material after the cradle leaves its car receiving position.

The under side of the plates 35 may be covered with rubber 35a or other non-metallic material. It will be noted by reference to Figs. 1, 4 and 5 that the members 33 and the plates 35 extend transversely of the cradle toward the dumping side thereof a distance such as to leave a restricted opening or throat at the top side of the car adjacent the dumping side of the cradle.

The rear ends of the members 33 have pivotally connected thereto forks 36 carried by rods 37 which in turn are connected at their lower ends to chains or other suitable flexible means 20, 38 anchored to the girder frame 22, as indicated at 39. The members 33 are also provided with downwardly extending portions 40 carrying at their lower ends pivotally mounted stops 41 which cooperate with stop lugs carried by the channels 24 of the sliding frames for a purpose later to be explained.

The channels 24 of the sliding frame are provided adjacent their lower ends with suitable bearing bosses 43 (see particularly Figs. 6 to 9, 30, inclusive), in which are rotatably mounted shafts 44, such shafts having one end extending through and beyond the bosses 43 and their opposite ends rotatably mounted in spaced apart parallel angle plates 45 secured to the upper side of the channels 26 and extending rearwardly beyond said channels. The first mentioned ends of the shafts 44 have fixed thereto pawls 46 adapted to cooperate with vertically extending racks 47 secured to the plates 23b of the standards 23 and 40, provided with arms 46a to which are connected one end of tension springs 48, the other ends of which are connected to pins or other means 49 carried by the channels 24. The shafts 44 between the angle plates 45 have fixed thereto hubs 45, 51 from which extend upwardly rods or plates 52. Links 53 are pivoted at their lower ends between the angle bars 45 rearwardly of the channels 26, while their upper ends are connected to the ropes 31 that extend to the counterweights 50 for the hood. The links 53 adjustably carry, intermediate their ends, rods 54 that extend toward the dumping side of the cradle when the cradle is in the vertical position.

The angle bars 28 of the sliding frame sections, as previously mentioned, extend above the channels 27 and these upwardly extending portions of the angle bars 28 have secured thereto the rear ends of bowed plate members 55 which extend in a direction transversely of the cradle 60 and toward the dumping side thereof.

Referring to Figs. 1 and 4, wherein the cradle and the hood therefor are shown in full lines when the cradle is in car receiving position, it will be noted that the clamp hooks 16 are elevated above the top edge of the car 15 and that the sliding frame sections of the hood are held in a raised position such that the members 55 are above the top edge of the car. In this connection it should be noted that the counterweights 30 connected to the sliding frame of the hood engage fixed stops 56 just prior to the cradle reaching its car receiving position, with the result that the further downward movement of the cradle effects a relative upward move- 75

ment of the sliding frame of the hood and thus moves the members 55 sufficiently above the top edge of the car, not only to clear such edge, but to allow cars of varying height to enter the 5 cradle. It will also be noted that the pivoted hoods proper are swung upwardly about the pivotal connection of the members 32 with the channels 27 of the sliding frame sections and the manner in which such upward swinging movement 10 of the hoods is accomplished will now be explained.

As previously stated, the rear ends of the members 33 are connected to the rods and chains 37, 38, the latter of which are anchored at their 15 lower ends to the girder frame 22 carried by the cradle. When the counterweights 38 engage the stops 56 and the cradle continues its downward movement to car receiving position there is, as previously stated, a relative upward movement 20 of the sliding frame sections of the hood. Since the rear ends of the members 33 are connected to the rods 37 it will be apparent that the chains 38 anchored to the girder frame 22 will pull downwardly upon the rods with the result that 25 the members 33 carrying the plates 35 of the hoods proper will be swung about their pivots to the full line position shown in Figs. 1 and 4.

Assuming the car 13, shown in Figs. 1 and 4, to be loaded with material to be dumped, and 30 that the vertical hoisting movement of the cradle has started, it will be seen that the clamp hooks 16 and the members 55 of the hood remain stationary relative to the cradle until the top edge of the car engages the same, after which the 35 hooks and the members travel vertically upwardly with the car and cradle. During the time that the members 55 and, of course, the sliding frame sections have remained relatively stationary with respect to the cradle as it commences 40 to travel vertically upwardly, the channels 24 of the frame sections will have become positioned relative to the standards 23, so that the pawls 46 carried by the channels 24 are in a position to cooperate with the vertically extending racks 47 on the standards 23. When the cradle reaches 45 the dumping point and commences its turning movement, the platen 12 will shift toward the dumping side of the cradle and bring the side of the car into engagement with the bumpers 15 and position the top edge of the car fully under the hooks 16. The turning movement of the car also causes the car clamp beams 18 to swing across the car and to engage the top edge thereof opposite to the dumping edge, it being noted 50 that clearance is provided between certain of the swinging hood members to accommodate the clamp beams, one of such beams being indicated in dash and dot lines between the two left-hand swinging hoods in Fig. 3. As is well understood 55 in the art, the rope 21 and the counterweight to which it is connected act to more tightly maintain the clamp beam in engagement with the top edge of the car the further over the cradle is tilted.

During the initial upward movement of the cradle the swinging hoods are permitted to swing downwardly by gravity and thereafter they bear upon the material in the car with the result that 60 the hoods restrain the shifting movement of the material toward the dumping side until the cradle has nearly reached full dumping position.

The tilting movement of the cradle also causes the ropes 31 to swing the links 53 from their vertical position to an angular position with respect 70 to the standards 23, as shown in Figs. 5 and 7.

This movement of the links 53 withdraws the rods 54 from engagement with the rods or plates 52, whereupon the tension springs 48 are free to rotate the pawls 46 and shafts 44 to bring the pawls into engagement with the racks 47 and thus 5 positively lock the sliding frame against outward movement relative to the standards 23 under the weight of the material in the car. The turning movement of the cradle also causes the center of gravity of the pivoted stops 41 to shift so that 10 said stops swing from a vertical position inwardly toward the stop lugs 42 until their lower ends engage therewith at which time the pivoted hoods proper are positively held against swinging outwardly away from the car by the weight 15 of the material in the car acting against the same.

When the cradle has turned to the full dumping position, the dot and dash showing in Fig. 1, it will be noted that all of the material in the 20 car must pass outwardly thereof between the ends of the hoods and the dumping edge of the car and that if the turning movement of the cradle tends to throw the material forcibly outwardly thereof the hoods will retard its movement and 25 cause a gradual exit thereof from the car thereby reducing the amount of breakage incident to the dumping operation.

After the car has been dumped and the cradle returns to a vertical position in the frame or tower 30 to be lowered therein, it will be seen that the links 53 will return to a substantially vertical position, such as shown in Figs. 6, 8 and 9 and that the rods 54 carried thereby will engage the rods or plates 52 to rock the shafts 44 and the pawls 46 35 against the action of the springs 48 and thus release the pawls from their engagement with the racks 47. The return movement of the cradle will also cause the pivoted stops 41 to swing away from their engagement with the stop lugs 42 and 40 assume a substantially vertical position. After the car has been dumped and is empty the pivoted hoods may only swing downwardly across the 45 car to a point where they engage with the members 55, as shown in dash and dot lines in Fig. 4, thus obviating the danger of the outer ends of the hood swinging into the interior of the car.

As previously stated, when the cradle has reached its car receiving position after the dumping operation, the clamp hooks 16 will be raised 50 out of engagement with the top edge of the car as will also the members 55, while the hoods will swing upwardly a substantial distance above the top of the car. The empty car may now be removed and a new car positioned upon the cradle, 55 it being noted that the upwardly swung hoods provide sufficient clearance for a car rider to accompany the loaded car onto the cradle in order to apply the brakes at the proper time to correctly position the same thereon.

It will also be noted that during the dumping or turning movement of the cradle the sliding frame sections are positively locked against outward movement and, since the members 55 engage the top of the car the frames assist or 60 cooperate with the car clamps to hold the car on the cradle.

It will further be noted that, since the pivoted hoods are positively locked during the dumping movement of the cradle against outward swing- 70 ing movement, the effectiveness of the hoods is assured, since there is no danger of the same swinging outwardly and allowing the material to be suddenly discharged from the car with a resultant breakage of the material.

Although a preferred embodiment of the invention has been illustrated and described herein, it should be understood that the invention is susceptible of various modifications and adaptations within the scope of the appended claims.

Having thus described our invention, we claim:

1. In a car dumper, a car receiving cradle adapted to be turned to dump a car thereon, a hood extending transversely of the cradle toward the dumping side thereof and adapted to bear upon the material in the car, means pivotally connecting said hood to said cradle, and means associated with said cradle and said hood for automatically swinging said hood upwardly as said cradle reaches car receiving position.

2. In a car dumper, a car receiving cradle adapted to be turned to dump a car thereon, a hood extending transversely of the cradle toward the dumping side thereof and adapted to bear upon the material in the car, means pivotally connecting said hood to said cradle, means for maintaining said hood against outward swinging movement during the turning of said cradle to car dumping position, and means associated with said cradle and said hood for automatically swinging said hood upwardly as said cradle reaches car receiving position.

3. In a car dumper, a car receiving cradle adapted to be turned to dumping position, car clamps adapted to clamp a car on said cradle during the dumping operation, pivoted means associated with said cradle for sliding movement relative thereto and extending transversely thereof toward the dumping side and adapted to partially cover a car on said cradle, and means for maintaining said first named means against outward swinging movement during the dumping operation.

4. In a car dumper, a car receiving cradle adapted to be turned to car dumping position, car clamps adapted to clamp a car on said cradle during the dumping operation, pivoted means associated with said cradle for sliding movement relative thereto and extending transversely thereof toward the dumping side and adapted to partially cover a car on said cradle, and means associated with said first named means and said cradle for maintaining said first named means against outward sliding movement relative to said cradle, said second named means being automatically rendered effective by the turning of the cradle to car dumping position.

5. In a car dumper, a car receiving cradle adapted to be turned to car dumping position, pivoted means associated with said cradle for sliding movement relative thereto and extending transversely thereof toward the dumping side and adapted to partially cover a car on said cradle, means for maintaining said first-named means against outward swinging movement, and means associated with said first-named means and said cradle for maintaining said first-named means against outward sliding movement relative to said cradle, said last two named means being effective during the turning of the cradle to car dumping position.

6. In a car dumper, a car receiving cradle adapted to be turned to car dumping position, pivoted means associated with said cradle for sliding movement relative thereto and extending transversely thereof toward the dumping side and adapted to partially cover a car on said cradle, means for maintaining said pivoted means against outward swinging movement, means for maintaining said pivoted means against outward sliding

movement relative to said cradle, said last two named means being effective during the turning of the cradle to car dumping position, and means for automatically swinging said pivoted means upwardly as said cradle reaches car receiving position.

7. In a car dumper, a car receiving cradle adapted to be turned to car dumping position, a frame mounted on and extending longitudinally of said cradle for vertical movement relative thereto, and a hood pivotally connected to said frame and extending transversely of the cradle toward the dumping side thereof.

8. In a car dumper, a car receiving cradle adapted to be turned to car dumping position, a frame comprising a plurality of sections independently mounted on said cradle for vertical movement relative thereto, and hoods pivotally connected to said sections and extending transversely of the cradle toward the dumping side thereof.

9. In a car dumper, a car receiving cradle adapted to be turned to car dumping position, a frame mounted on said cradle for vertical movement relative thereto, a hood pivotally connected to said frame and extending transversely of the cradle toward the dumping side thereof, and means associated with said frame and said hood for maintaining said hood against outward swinging movement during the turning of said cradle to car dumping position.

10. In a car dumper, a car receiving cradle adapted to be turned to car dumping position, a frame mounted on said cradle for vertical movement relative thereto, a hood pivotally connected to said frame and extending transversely of the cradle toward the dumping side thereof, a stop lug carried by said frame, and a pivoted stop carried by said hood and cooperating with said lug to maintain said hood against outward swinging movement during the turning of said cradle to car dumping position.

11. In a car dumper, a car receiving cradle adapted to be turned to car dumping position, a frame mounted on said cradle for vertical movement relative thereto, a hood pivotally connected to said frame and extending transversely of the cradle toward the dumping side thereof, and means for maintaining said frame against outward movement relative to said cradle during the turning of said cradle to car dumping position.

12. In a car dumper, a car receiving cradle adapted to be turned to car dumping position, vertical standards carried by said cradle opposite to the dumping side thereof, a frame mounted for movement along said standards, a hood pivotally connected to said frame and extending transversely of the cradle toward the dumping side thereof, racks carried by said standards, pawls carried by said frame, means for urging said pawls into engagement with said racks, and means for rendering said last-mentioned means ineffective except during the turning of said cradle to car dumping position.

13. In a car dumper, a car receiving cradle adapted to be turned to car dumping position, a frame mounted on said cradle for vertical movement relative thereto, a hood pivotally connected to said frame and extending transversely of the cradle toward the dumping side thereof, means for causing upward movement of said frame relative to the cradle, and means for causing upward swinging movement of said hood relative to said frame, both of said means being automatically effective as said cradle reaches car receiving position.

14. In a car dumper, a car receiving cradle adapted to be raised and turned to car dumping position, a frame mounted on said cradle for vertical movement relative thereto, means for causing a vertical upward movement of said frame relative to said cradle prior to said cradle reaching car receiving position, a hood pivotally connected to said frame and extending transversely of the cradle toward the dumping side thereof, and means interconnecting said hood and said cradle and effective during said upward movement of said frame to swing said hood upwardly.
15. In a car dumper, a car receiving cradle adapted to be turned to car dumping position, car clamps carried by said cradle and effective during the turning of said cradle to clamp a car thereon, and a plurality of pivoted hoods mounted on said cradle and extending transversely thereof toward the dumping side, certain of said hoods being spaced apart to accommodate said clamps when in car clamping position.
16. In a car dumper, a car receiving cradle adapted to be turned to car dumping position, a frame carried by said cradle and movable vertically with respect thereto, said frame being provided with members extending laterally therefrom and toward the dumping side of the cradle and adapted to engage the top edge of a car thereon, and a pivoted hood mounted on said frame and extending toward the dumping side of the cradle.
17. In a car dumper, a car receiving cradle adapted to be turned to car dumping position, a frame carried by said cradle and movable vertically with respect thereto, said frame being provided with members extending laterally therefrom and toward the dumping side of the cradle and adapted to engage the top edge of a car thereon when the cradle leaves car receiving position and a pivoted hood mounted on said frame and extending toward the dumping side of the cradle and adapted when the cradle is in other than car receiving position either to bear upon the material in the car when the latter is fully loaded or to bear upon said members when the car is empty or not fully loaded.
18. In a car dumper, a car receiving cradle adapted to be turned to car dumping position, vertical standards carried by said cradle opposite to the dumping side thereof, a frame mounted for movement along said standards, a hood pivotally connected to said frame and extending transversely of the cradle toward the dumping side thereof, cooperating racks and pawls carried by said frame and standards, means for urging said pawls into engagement with said racks, and means for rendering said last mentioned means ineffective except during the turning movement of said cradle to car dumping position.
19. In a car dumper, a car receiving cradle adapted to be turned to car dumping position, a frame mounted on said cradle for vertical movement relative thereto, a hood pivotally connected to said frame and extending transversely of the cradle toward the dumping side thereof, means for causing upward movement of said frame relative to the cradle, means for causing upward swinging movement of said hood relative to said frame, both of said means being automatically effective as said cradle reaches car receiving position, and automatic means maintaining said frame against outward movement during the turning of said cradle to car dumping position.
20. In a car dumper, a car receiving cradle adapted to be turned to car dumping position, a frame mounted on said cradle for vertical movement relative thereto, a hood pivotally connected to said frame and extending transversely of the cradle toward the dumping side thereof, means for causing upward movement of said frame relative to the cradle, means for causing upward swinging movement of said hood relative to said frame, both of said means being automatically effective as said cradle reaches car receiving position, and means for automatically maintaining said hood against outward swinging movement during the turning of said cradle to car dumping position.
21. In a car dumper, a car receiving cradle adapted to be turned to car dumping position, a frame mounted on said cradle for vertical movement relative thereto, a hood pivotally connected to said frame and extending transversely of the cradle toward the dumping side thereof, means for causing upward movement of said frame relative to the cradle, means for causing upward swinging movement of said hood relative to said frame, both of said means being automatically effective as said cradle reaches car receiving position, means for maintaining said frame against outward movement relative to said cradle, and means for maintaining said hood against outward swinging movement relative to said frame, both of said last two means being automatically effective during the turning of said cradle to car dumping position.
22. In a car dumper, a car receiving cradle adapted to be turned to car dumping position, a frame comprising a plurality of sections independently mounted on said cradle for vertical movement relative thereto, hoods pivotally connected to said sections and extending transversely of the cradle toward the dumping side thereof, and means for independently and automatically maintaining said frame sections against outward movement during the turning of said cradle to car dumping position.
23. In a car dumper, a car receiving cradle adapted to be turned to car dumping position, a frame comprising a plurality of sections independently mounted on said cradle for vertical movement relative thereto, hoods pivotally connected to said sections and extending transversely of the cradle toward the dumping side thereof, and means for automatically and independently maintaining said hoods against outward swinging movement during the turning of said cradle to car dumping position.
24. In a car dumper, a car receiving cradle adapted to be turned to car dumping position, a frame comprising a plurality of sections independently mounted on said cradle for vertical movement relative thereto, hoods pivotally connected to said sections and extending transversely of the cradle toward the dumping side thereof, means for automatically and independently maintaining said frame sections against outward movement, and means for automatically and independently maintaining said hoods against outward swinging movement, both of said means being effective during the turning of said cradle to car dumping position.
25. In a car dumper, a car receiving cradle adapted to be turned to car dumping position, a frame comprising a plurality of sections independently mounted on said cradle for vertical movement relative thereto, hoods pivotally connected to said sections and extending transversely of the cradle toward the dumping side there-

of, means for causing independent upward movement of said frame sections relative to the cradle, and means for causing independent upward swinging movement of said hoods relative to said frame sections, both of said means being automatically effective as said cradle reaches car receiving position.

26. In a car dumper, a car receiving cradle adapted to be turned to car dumping position, a frame comprising a plurality of sections independently mounted on said cradle for vertical movement relative thereto, hoods pivotally connected to said sections and extending transversely of the cradle toward the dumping side thereof, means for causing independent upward movement of said frame sections relative to the cradle, means for causing independent upward swinging movement of said hoods relative to said frame sections, both of said means being automatically effective as said cradle reaches car receiving position, means for independently maintaining said frame sections against outward movement, and means for independently maintaining said hoods against outward swinging movement, both of said last two means being automatically effective during the turning of said cradle to car dumping position.

27. In a car dumper, a car receiving cradle adapted to be turned to dumping position, car clamping means, pivoted means associated with said cradle for sliding movement relative thereto and extending transversely thereof toward the dumping side and adapted to overlie the car on said cradle and form a cover therefor, and means for automatically swinging said pivoted means upwardly relative to the car as said cradle approaches car receiving position.

28. In a car dumper, a car receiving cradle adapted to be turned to dumping position, car clamping means, pivoted means associated with said cradle for sliding movement relative thereto and extending transversely thereof toward the dumping side and adapted to overlie a car on said cradle and form a cover therefor, and means for causing automatically a sliding movement of said pivoted means relative to said cradle as the latter approaches car receiving position.

29. In a car dumper, a car receiving cradle adapted to be turned to dumping position, car clamping means, pivoted means associated with said cradle for sliding movement relative thereto and extending transversely thereof toward the dumping side and adapted to overlie a car on said cradle and form a cover therefor, and means for automatically causing an upward sliding movement and an upward swinging movement of said pivoted means relative to the cradle as the latter approaches car receiving position.

30. In a car dumper, a car receiving cradle adapted to be turned to car dumping position, a frame comprising a plurality of sections independently mounted on said cradle for vertical movement relative thereto, hoods pivotally connected to said section and extending transversely of the cradle toward the dumping side thereof, and means for causing upward swinging movement of said hoods relative to said frame sections and automatically effective as said cradle approaches car receiving position.

31. In a car dumper, a car receiving cradle adapted to be turned to car dumping position, car clamping means, pivoted means associated with said cradle for sliding movement relative thereto and extending transversely thereof toward the dumping side and adapted to overlie a car on said cradle and form a cover therefor, and means associated with said pivoted means and said cradle for maintaining said pivoted means against outward sliding movement relative to said cradle during the car dumping operation, said last named means being automatically rendered ineffective while the cradle is in upright position and before it reaches car receiving position.

32. In a car dumper a cradle adapted to be tilted to dump a car thereon, car clamping means, a hinged hood adapted to retard the outflow of material from said car during the dumping operation, said clamping means and said hood being movable vertically relative to said cradle, and means for automatically moving said clamping means and said hood vertically as said cradle approaches the car receiving position.
